MACHINE FOR MAKING COATED WOVEN
TUBESJoseph A. Kennedy, Pawtucket, R. I., assignor to
Anaconda Wire & Cable Company, New York,
N. Y., a corporation of Delaware

Application April 21, 1933, Serial No. 667,190

18 Claims. (Cl. 139—13)

The invention aims to provide improvements for circular looms and the like with particular reference to means for applying an impervious coating or lining, such as rubber to the interior 5 or to both the interior and exterior of the tubing during the time that the component warp and filling strands of such tubing are interwoven. An important feature of the invention relates to the provision of a hollow mandrel, which crosses the 10 plane at which the warp and filling strands are interwoven, the mandrel being entirely open at the end, so as to permit of coating material being discharged in an axial direction. Coating with the open-ended mandrel, I provide a flexibly or 15 floatingly supported element adapted to properly distribute the coating material over the interior wall thereof, this element also being adapted to exert a slight lateral pressure on the coating material, so as to smooth and even the coating.

20 While not limited thereto, the present invention is well suited for use in combination with the type of circular loom shown in my prior Patent 1,327,677, granted January 13, 1920.

The present invention will be more fully apparent from the following detailed description when read in connection with the accompanying drawings, in which—

Fig. 1 is a vertical sectional view of a circular loom similar to that shown in my prior patent, 30 but modified to illustrate improvements herein-after more fully disclosed;

Fig. 2 is a detail view on an enlarged scale illustrating attachments to the loom which constitute the chief features of the present improvement;

Fig. 3 is an enlarged detail of the hollow mandrel and floatingly supported distributing member;

Fig. 4 is a view of the distributing member of 40 Fig. 3 detached;

Fig. 5 illustrates a modified form of securing means for the distributing element;

Fig. 6 is a detail side view of a wiping nipple shown in section in Fig. 2;

Fig. 7 is a plan view thereof.

Although the invention comprises as an element thereof a circular loom, yet this part of the combination is not restricted to any particular type of loom. For illustrative purposes, I have 50 chosen a circular loom of the type shown in Patent 1,327,677, granted to me on January 13, 1920. So much of the loom as is material for an understanding of the present invention is shown in Fig. 1. In this figure, 10 and 12 represent shut- 55 tles which travel in the circular path about a

mandrel 14 being guided by track 16 and propelled in a manner well known in the art. The shuttles lay the filling threads in a conventional and well known manner in the shed formed between warp threads, indicated diagrammatically at 18, 20, 22 and 24. The warp threads pass through eyes 26 on heddles which are reciprocated by known cam mechanism 27 so as to change the shed and thus cause the warp threads to pass successively over and under the successive turns 60 or convolutions of the filling or shuttle threads. The fabric thus formed by interweaving of the warp and shuttle threads about the mandrel 14 forms a tube *t* which is withdrawn through a guide 28 as fast as its construction progresses, 65 whereby the weaving constantly takes place at substantially the same plane or level, and the tube under construction is led away, by an overhead feed-wheel (not shown) in the direction of the arrow *x*, at a speed equal to the rate at which its 70 length is increased by the addition of successive turns or convolutions of the filling thread.

The mandrel 14 besides serving as the form about which the filling threads are wound in the weaving of the tubular web also serves the further purpose of a conduit for conducting fluid or semi-fluid coating material into the interior of the newly constructed tube for the purpose of providing a coating or lining therefor.

The apparatus, as thus far described in detail, is substantially identical with that shown and described in my previous patent. In my former patent, the coating material emanating from the mandrel was discharged laterally through openings in fixed member secured to 85 the end thereof.

According to my present invention, the mandrel instead of being closed at the end is open ended and the coating material is expelled axially and uniformly distributed by a floatingly 90 supported distributing element, positioned adjacent the open ended mandrel. This enables me to discharge the coating material in an uninterrupted endwise directed stream of substantially 95 annular form, the annular form of stream being made possible by the coaction and relationship between the open ended tube and the distributing element.

As best shown in detail in Fig. 3, the distributing element, indicated at 30, is of substantially 100 cylindrical form provided with a rounded extremity 32 at its outer end and a rounded end 34 opposite the open end 36 of the mandrel. The distributing element in the embodiment illustrated in Figs. 1 to 4 inclusive, is floatingly sup-

ported in spaced relationship to the open end of the mandrel by means of a fine flexible steel wire 38 secured to an anchorage plug 40 having screw threads 42, which engage similar threads formed in the enlarged base 44 to which the mandrel is secured.

The flexible supporting member 38 extends substantially axially of the mandrel. The coating material which may be rubber latex is forced from a supply tank 46 by means of air pressure from a suitable source under control of the shut-off valve 48. Connected with the supply tank, there is a pipe 50 having a control valve 52 therein, this pipe leading to an enlarged chamber 54 formed in the base 44 to which the hollow spindle is secured. As thus arranged, it is apparent that the air pressure will cause the rubber latex or other coating material to be expelled in an annular stream from the open end 36 of the mandrel. As the coating material is discharged, the floatingly supported distributing element will automatically center itself with respect to the component strands formed thereabout and will thus insure a uniform distribution of the coating material on all parts of the interior raceway of the tube. The distributing element is of sufficient length to prevent the rubber latex from by-passing it and thus plugging up the tube. I regard it of extreme importance to floatingly or flexibly support the distributing element. This is especially true in coating tubing of small size of the order of $\frac{1}{2}$ an inch inside diameter or less. I have found in practice that with the methods and apparatus heretofore in use, it is extremely difficult to control the even distribution of the coating material on all parts of the interior raceway. It is my belief that this difficulty is due largely to the fact that as the tube leaves, the weaving spindle, being of flexible material, moves slightly out of alignment, thus leaving one side of the tube heavily coated and the other side with a thinner coating. This difficulty is overcome by the present improvement, which contemplates the use of a floatingly supported distributing member.

The thickness of coating applied can be controlled to an accurate degree by varying the diameter of the member 30 and a nicety of regulation can be obtained by adjusting the element 30 toward or from the open end of the mandrel, such adjustment being effected by turning the threaded plug 40.

The floating support for the distributing element may take the form of the fine steel wire 38 shown in Figs. 1 to 4 inclusive. Such a flexible support will permit the distributing element to float laterally in right or left so as to become centered with the tube. But, the wire being relatively stiff will not permit the distributing element to rise and fall. I contemplate, however, in some cases, to permit the floating element to also rise and fall and to this end I sometimes substitute for the wire 38, of Figs. 1 to 4, a piece of fine cotton or similar fabric thread, such as shown at 56 in Fig. 5, this thread being secured at one end to a wire loop or eye 58 formed on the lower part of the distributing element 30^a and at the other end to a wire loop or eye 60 carried by the screw plug 42^a. The thread or string 56, it will be understood, being limp will permit the distributing element 30^a to rise and fall depending upon the volume of rubber latex or other coating material flowing outwardly from the open end of the hollow mandrel 14.

The pipe 50 for supplying coating material to

the hollow mandrel enters through the side of the loom instead of axially as in my former patent. To make room for such a side entering pipe, one of the heddles is removed and an overhead heddle substituted therefor. Such overhead heddle is actuated by means of a suitable connection with another of the typical cam actuated heddles.

A further aspect of the invention relates to means for evening and smoothing any part of the coating material, which may permeate between the interstices of the warp and filling strands, or to smooth and distribute such coating material as may be applied to the exterior of the tube. To these ends, I provide a tubular shell 62 which surrounds the exterior of the woven tube, this shell being secured to a hub 64 of a fixed guide bracket 66. At its upper end, the shell carries a split bushing 68 secured in place by a set screw 70.

As the woven and interiorly coated tube passes through the opening 72 in the bushing, any part of the coating material which has permeated through to the exterior thereof is somewhat smoothed and evened by the bushing. The woven tube then progresses through a pan 74 supported on top of the shell 62. This pan 74 may in some cases be filled or partially filled with a substance for impregnating or coating the exterior of the woven tube. Regardless of whether or not additional coating or impregnating material is supplied to the pan 74, I provide a cup-shaped wiping nipple 76 of rubber or the like having a central wiping opening 78 through which the interiorly coated tube passes and also having a number of additional holes 80 for bleeding the excess material. This wiping nipple 76 is preferably floatingly supported by a plurality of flexible strings 82 secured to studs 84 provided at the upper end of the pan 74, these strings passing through suitable apertures 86 located at properly spaced points around the periphery of the lower end of the wiping nipple.

The cupped form of the wiping nipple is important for it serves to retain an annular body of the coating material in contact with the woven tube as the latter is fed away from the weaving point. The excess material bleeds through the holes 76 and flows over the exterior of the nipple and drips back into the pan 74. The resiliency of the cup gives a yielding wipe and the flexibility of the strings coupled with such resiliency provides a combination which effectively keeps the wiping nipple centered regardless of any lateral motion of the completed tube as it is fed from the machine.

The pan 74 has an overflow spout 88 and an overflow cup 90 is secured to the lower end of the shell 62 for catching any overflow of material. There is also a disc or plate 92 secured adjacent the base of the hollow mandrel so as to prevent any overflowing coating material from flowing into the rotating member 94, which carries the cams 27 for elevating and depressing the heddles.

From the foregoing, it is apparent that the invention provides improved coating distributing means adapted for use in combination with a collection of coating instrumentalities constructed, arranged and operable to produce a woven fabric tube at a given plane. It is also apparent that one aspect of the invention relates to the provision of a hollow open ended mandrel crossing the weaving plane adapted to effect an endwise discharge of coating material into the interior of the newly woven tube and a coating element

flexibly supported beyond the open end of the mandrel, which is effective to uniformly distribute coating material over the inner surface of the tube. It is apparent that the invention also contemplates the improvements just referred to in combination with means effective to wipe such coating material as permeates through to the exterior wall of the tube, or for wiping the coating material applied to the exterior of the tube, so as to impart a smooth substantially uniform outer finish thereto.

While I have described the specific details of the particular embodiment of the invention herein illustrated, it is to be understood that the description and drawings are to be interpreted in an illustrative rather than a limiting sense and that the appended claims are to be construed as broadly as is consistent with the prior state of the art.

20 What I claim is:—

1. A machine for constructing and lining tubular fabrics comprising in combination a collection of coacting instrumentalities constructed, arranged and operable to produce a tubular fabric at a given plane, a hollow open ended mandrel crossing said plane and entering the newly constructed tube, means for discharging a fluid material therein from the end of said mandrel and an element flexibly supported and spaced beyond the open end of said mandrel constructed and arranged to evenly distribute and smooth the fluid material over the interior surface of said newly formed tube.

2. A machine for constructing and lining tubular fabrics comprising in combination a collection of coacting instrumentalities constructed, arranged and operable to produce a tubular fabric at a given plane, a hollow open ended mandrel crossing said plane and entering the newly constructed tube, means for discharging a fluid material therein from the end of said mandrel, an element for distributing and smoothing said material and a flexible selfaligning member having one end secured to said element and another end secured to a fixed support.

3. A machine for constructing and lining tubular fabrics comprising in combination a collection of coacting instrumentalities constructed, arranged and operable to produce a tubular fabric at a given plane, a hollow open ended mandrel crossing said plane and entering the newly constructed tube, means for discharging a fluid material therein from the end of said mandrel and a floatingly supported distributing element spaced beyond the open end of said mandrel.

4. A machine for constructing and lining tubular fabrics comprising in combination a collection of coacting instrumentalities constructed, arranged and operable to produce a tubular fabric at a given plane, a hollow open ended mandrel crossing said plane and entering the newly constructed tube, means for discharging a fluid material therein from the end of said mandrel, a distributing element movable relatively to said mandrel, a flexible member secured thereto and an anchorage for said flexible member.

5. A circular loom including a mandrel and instrumentalities for interweaving warp threads with a helical weft thread about the mandrel, said mandrel being hollow and open at its outer end, an element floatingly supported adjacent thereto and means for conducting a coating material to said mandrel, under such pressure as to cause ejection of the material from the outer end of the mandrel.

6. In apparatus for producing internally coated or lined tubes, a hollow mandrel, means for interconnecting the thread-like elements of a tube about the mandrel, means for conveying a fluid material through said mandrel to the interior of the tube formed thereabout, a smoothing element and flexible supporting means therefor.

7. In apparatus for producing internally coated or lined tubes, a hollow mandrel, means for interconnecting the thread-like elements of a tube about the mandrel, means for conveying a fluid material through said mandrel to the interior of the tube formed thereabout, a smoothing element and a flexible member extending through the mandrel and supporting said element beyond the open end thereof.

8. A machine for constructing and lining tubular fabrics comprising in combination a collection of coacting instrumentalities constructed, arranged and operable to produce a tubular fabric at a given plane, a hollow open ended mandrel crossing said plane and entering the newly constructed tube, means for discharging a fluid material therein from the end of said mandrel, a distributing member and a flexible wire support therefor disposed substantially axially of said hollow mandrel.

9. An attachment for an apparatus for internally coating tubes formed of interconnected thread-like elements comprising, a hollow open ended mandrel about which the elements are adapted to be interconnected and a distributing element floatingly supported beyond the open end of the mandrel, and means for conducting a coating material to the mandrel under such pressure as to cause the ejection of the material between the end of said mandrel and said distributing element.

10. An attachment for an apparatus for internally coating tubes formed of interconnected thread-like elements comprising, a hollow open ended mandrel about which the elements are adapted to be interconnected, a distributing element, a flexible member supporting the latter beyond the end of the mandrel and means for conducting a coating material to the mandrel under such pressure as to cause the ejection of the material between the end of said mandrel and said distributing element.

11. An attachment for an apparatus for internally coating tubes formed of interconnected thread-like elements comprising, a hollow open ended mandrel about which the elements are adapted to be interconnected, a substantially cylindrical element flexibly supported beyond the open end of said mandrel and means for conducting a coating material to the mandrel under such pressure as to cause the ejection of the material between the end of said mandrel and said cylindrical element.

12. In a circular loom for weaving tubular fabric, a hollow mandrel about which the fabric is adapted to be woven, a distributor element, flexible means supporting the latter and means effective to discharge coating material into the newly woven tube axially between the distributor element and the end of said mandrel.

13. In a circular loom for weaving tubular fabric, a hollow mandrel about which the fabric is adapted to be woven, means effective to discharge material therefrom, and means for smoothing the material which permeates to the exterior of the tube comprising a member of resilient mate-

rial having a wiping opening through which the woven and coated tube passes.

14. In a circular loom for weaving tubular fabric, a hollow mandrel about which the fabric is adapted to be woven, means effective to discharge material therefrom, and means for smoothing the material which permeates to the exterior of the woven tube comprising a cupped member of rubber or the like having one opening through which the woven and coated tube passes and other openings for bleeding the excess coating material.

15. In a circular loom for weaving tubular fabric, a hollow mandrel about which the fabric is adapted to be woven, means effective to discharge coating material therefrom, means for smoothing the material which permeates to the exterior of the woven tube comprising a member of resilient material having a wiping opening through which the woven and coated tube passes, flexible supporting members secured to said member and fixed anchorages for the latter.

16. In a circular loom for weaving tubular fabric, a hollow mandrel about which the fabric is adapted to be woven, means effective to discharge material therefrom, and means for smoothing the material which permeates to the exterior of the

tube comprising a cupped member of resilient material having a wiping opening through which the woven and coated tube passes, a pan carrying a bushing adapted to guide the tubing and flexible string-like supports for the cupped member secured to said pan.

17. In a circular loom for weaving tubular fabric, a mandrel about which the fabric is adapted to be woven, a pan surrounding the newly formed woven tube and a member of resilient material having a wiping opening therein through which the tubing passes and flexible means anchoring said member to the pan.

18. In a circular loom for weaving tubular fabric, a mandrel about which the fabric is adapted to be woven, said mandrel being vertically disposed, a fixed support above the latter carrying a shell, whose lower end is provided with a guide opening surrounding the mandrel, a bushing secured to the shell and having a guide opening therein axially aligned with the mandrel, a pan surrounding the bushing adapted to hold a coating material, a cupped resilient member having a wiping opening substantially in axial alignment with said mandrel and flexible means for anchoring said member to said pan.

JOSEPH A. KENNEDY.
